UNITED STATES PATENT OFFICE.

FRANK B. DEMING, OF WARREN, OHIO.

HAND-BUFFER.

No. 881,557.

Specification of Letters Patent. Patented March 10, 1908.

Application filed October 31, 1907. Serial No. 400,092.

To all whom it may concern:

Be it known that I, FRANK B. DEMING, a citizen of the United States, residing at Warren, in the county of Trumbull and State 5 of Ohio, have invented certain new and useful Improvements in Hand-Buffers; and I do hereby declare the following to be a full, clear, and exact description of the invention, such as will enable others skilled in the art 10 to which it appertains to make and use the same.

My invention in its broadest sense relates to the art of grinding and polishing articles of manufacture; but more particularly stated 15 it comprises a new and improved construction of hand-buffer for shop uses, designed and employed chiefly for finishing and polishing metal articles in the usual course of production, while held in a vise, a lathe, or 20 the hand of a mechanic. It is also well suited for various analogous uses and for similarly finishing articles of wood or other materials such as patterns, or, when provided with suitable abrading surfaces, for 25 scouring, polishing and sharpening articles of cutlery and edge tools.

The invention consists in the construction, novel combination and arrangement of parts hereinafter described and particularly pointed 30 ed out in the claims following.

In the accompanying drawings which form part of this application, and whereon like numerals of reference indicate corresponding parts in the several views: Figure 1 represents in perspective my invention in its 35 entirety. Fig. 2 is an edge view of the same. Figs. 3 and 4 are longitudinal central sections through the clamping ends of the tool. Fig. 5 is an enlarged central section taken in 40 a plane at right angles to that of Fig. 3, and, Figs. 6 and 7 are detached perspective views of the clamps.

Reference being had to the drawings and numerals thereon, 1 indicates the buffer body 45 preferably of hard wood or other suitable material light in weight, of rectangular cross section as shown in the present drawings, and finished at one end with an integral handle 2. On both sides of the handle end 50 of body 1 are fixed clamps 3, 3 formed of sheet metal folded upon itself as at 4, 4 to produce open ended pockets 5, 5, and countersunk or depressed flush with the surface of said body portion.

55 At its opposite or outer end the body 1 is provided with an end wear-plate 6 threaded

as at 7 to receive an adjusting screw 8 the latter shouldered at 9 as shown. Mounted upon the shoulder 9 of said screw 8 is a relatively adjustable clamp 10 having a central perforation 11 through which projects the head of screw 8. This double adjustable clamp 10 embraces the extremity of body 1 and its wear-plate 6 aforesaid, and is preferably formed of sheet metal folded upon itself 60 at 12, 12 to produce open ended pockets 13, 13 on both sides of the body portion 1; similar to the aforesaid pockets 5, 5 of the relatively fixed clamps 3, 3. The edges of all clamps 3 and 10 are slightly roughened by 70 projecting clutch-points 14, which assist in retaining in operative position strips of emery cloth or other abrading material 15, 15, as clearly shown by the drawings.

This being a description of my present invention, its use and operation are too self-evident to require more than passing notice; it will be noted, however, that the abrading material folded at its ends is first introduced 75 into the relatively fixed and adjustable 80 pockets 5 and 13 upon both sides of the body portion 1. By agency of screw 8 and its shoulder 9 the adjustable clamp 10 may thereupon be backed off from wear plate 6 thus placing the abrading material under 85 tension, and the tool in condition for use.

This being a description of my invention in its preferred form of construction, it should be understood that various changes 90 may be made and substituted for the form and arrangement of parts herein shown and described without in the least departing from the spirit of the invention which will now be set forth in the claims following.

1. In a hand buffer the combination with 95 a body portion, of an adjustable end-clamp formed of sheet metal folded upon itself to produce an open ended pocket, an adjusting screw interposed between said body portion and end-clamp, and a strip of abrading 100 material secured at one end in said pocket and at its opposite end to the body portion aforesaid, substantially as described.

2. In a hand buffer the combination with 105 a body portion, of an adjustable outer end-clamp formed of sheet metal folded upon itself to produce open ended pockets on both sides of said body portion, projecting clutch-points on the edges of said folded clamp member, and a strip of abrading material extending 110 from each of said pockets over said clutch-points and secured at the opposite end to the

body portion aforesaid, substantially as described.

3. In a hand buffer the combination with a body portion, of an adjustable outer end-clamp embracing said body portion formed of sheet metal folded upon itself to produce open ended pockets, an adjusting screw shouldered upon and projecting through said clamp, and strips of abrading material each secured at one end in the aforesaid pockets and at the opposite end in similar pockets fixed with relation to the body portion aforesaid, substantially as described.

4. In a hand buffer the combination with a body portion, of relatively fixed and adjustable clamps formed of sheet metal folded upon itself to produce open ended pockets, and a strip of abrading material secured at

opposite ends in the pockets aforesaid, substantially as described.

5. In a hand buffer, the combination with a body portion having upon each side of its longitudinal center relatively fixed and adjustable clamps formed of sheet metal folded upon itself to produce oppositely disposed open ended pockets, projecting clutch-points on the edges of said clamps, and a strip of abrading material secured at opposite ends in each set of said pockets, substantially as described.

In testimony whereof I affix my signature in presence of two subscribing witnesses.

FRANK B. DEMING.
